PORTABLE AIR PUMP

William S. Vaughan, Bothell, Wash.

Application September 14, 1953, Serial No. 26,799

Term of patent 7 years

(Cl. D65—1)

FIG. 1.

FIG. 3.

FIG. 4.

FIG. 2.

To all whom it may concern:

Be it known that William S. Vaughan, a citizen of the United States, residing at Bothell, Washington, has invented a new, original, and ornamental Design for a Portable Air Pump, of which the following is a specification, reference being had to the accompanying drawing, forming a part thereof, in which

Figure 1 is a perspective view of a portable air pump, showing my new design;

Figure 2 is an end elevation of the same on a reduced scale;

Figure 3 is a top plan view of the same on a reduced scale; and

Figure 4 is an elevation of the same showing the end opposite that viewed in Figure 2.

I claim:

The ornamental design for a portable air pump, as shown.
